UNITED STATES PATENT OFFICE.

WILLIAM W. FARNSWORTH, OF SCRANTON, MISSISSIPPI.

COTTON-PICKING MACHINE.

947,483.

Specification of Letters Patent. Patented Jan. 25, 1910.

Application filed September 14, 1908. Serial No. 452,970.

To all whom it may concern:

Be it known that I, WILLIAM W. FARNSWORTH, a citizen of the United States, residing at Scranton, in the county of Jackson and State of Mississippi, have invented certain new and useful Improvements in Cotton-Picking Machines, of which the following is a specification.

This invention relates to improvements in cotton picking machines in which there is employed mechanical means adapted to be directed by an attendant for picking or drawing the cotton from the bolls, and improved means for conveying away the cotton after the latter has been removed from the plants.

A further object is to provide improved means for loosening or separating the cotton in the boll.

20 A further object is to provide an improved picker, and improved means for removing or stripping the cotton from the picker.

A further object is to provide an improved mechanical and pneumatic picking nozzle and improved means for controlling a blast of air through the nozzle.

A further object is to provide improved means for varying the suction of the nozzles.

30 A further object is to provide an improved machine of this character which will be simple and durable in construction and effective and efficient in operation.

To the attainment of these ends and the accomplishment of other new and useful objects, as will appear, the invention consists in the features of novelty in the construction, combination and arrangement of the several parts hereinafter more fully described and claimed and shown in the accompanying drawings, illustrating an embodiment of the invention, and in which—

Figure 1 is a side elevation of an improved machine of this character constructed in accordance with the principles of this invention. Fig. 2 is an enlarged detail sectional view of one of the picking nozzles. Fig. 3 is an elevation of the mouth of the nozzle. Fig. 4 is an enlarged detail sectional view of the valve and mechanism for controlling the degree of suction or vacuum in the nozzles.

Referring more particularly to the drawings and in the present exemplification of the invention the numeral 10 designates a suitable vehicle which is preferably mounted upon wheels and upon this vehicle is

mounted the operating mechanism for the pickers. This vehicle may be of any suitable construction and is adapted to receive the cotton from the nozzles after it is picked from the plants.

Mounted upon the vehicle and in any desired or suitable position is a suitable suction fan or vacuum creating device 11, extending from the casing of which is a suitable tubular member 12 which may be of any desired size and length and to which the flexible tubes 13 are connected, these tubes 13 having communication with the tubular member 12. Any number of these flexible tubes 13 may be provided according to the number of operators and the number of plants it is desired to pick at the same time. In the present exemplification of the invention only two of such tubes are shown and secured to the free extremity of each of the tubes is a picking nozzle designated generally by the reference numeral 14. This nozzle is provided with a conical extremity 15 and the other extremity of the nozzle is preferably reduced as shown and is secured respectively to the extremity of the flexible tubular members 13 by telescoping one extremity with the other. The conical extremity 15 of the nozzle is preferably offset laterally with respect to the body portion thereof and is provided with a suitable aperture in the top of the offset portion projecting into which is a circumferential extension 16 preferably in the form of a ring and a collar 17, of a diameter somewhat larger than the diameter of the opening which is surrounded by the ring 16, is located within said opening to form a closure therefor and this collar 17 is provided with a peripheral groove 18 which is adapted to receive the ring 16 so that the latter will form a support and bearing for the collar 17 whereby the latter may be freely rotated.

Surrounding the extremity of the nozzle 15 is a tubular member 19 which is provided with a plurality of nozzles 20 extending into and in a direction transverse to the opening of the picker nozzle. The nozzles 20 are preferably inclined as shown so as to direct a plurality of blasts of air across the extremity of the nozzle inward at an oblique angle to the periphery and in a plane perpendicular to the longitudinal axis of the nozzle to cause a whirling motion of the air within the picker nozzle. Any suitable means may be provided for supplying the

2
tubular member 19 with air to be directed from the nozzles 20. A suitable and efficient means for accomplishing this purpose comprises a compressed air chamber 21, which may be supplied with air from a suitable air pump 22, which latter may be operated from a suitable gear 23 through the medium of a pitman rod 24 and this gear 23 may be rotated from a suitable motor 25 through the medium of a connecting belt 26. A supply pipe 27 may be provided leading from the pump 22 to the compressed air chamber 21.

Extending from the chamber 21 is a suitable tubular member 28, which may be of any desired size and length according to the number of picker nozzles 15. Extending from this tubular member 28 are suitable tubular flexible members 29, which extend with the tubular members 13 to the picker nozzles 15, the free extremities of the tubular members 29 being respectively connected to one extremity of a tubular member 30 which is supported by the picker nozzle 15 and which has communication with the tubular member 19 so that the air supplied from the compressed air chamber 21 will be delivered into the tubular member 19 through the tubular members 29, 30. If desired, a suitable valve 31 may be provided in either the tubular member 29 or 30, which valve is adapted to normally close the passage through the tubular member to shut off the supply of air from the nozzles 20 to enable the operator to place the picker nozzle adjacent the cotton boll before a blast of air is delivered through the nozzles 20. When the picker nozzle is in proper position with respect to the plant, the operator may open the valve 31 to permit the air to flow to the nozzles 20 and through the medium of this valve 31 he is enabled to regulate the blasts of air thus delivered.

The chamber 12 which has communication with the casing 11 of the suction or vacuum creating device is provided with an opening 32 to the outside air and a suitable valve 33 may be provided for closing this opening. Any suitable means may be provided for controlling this valve 33 and in the present exemplification of the invention there is provided a rod 34, one extremity of which is secured to the valve 33 and passes through a suitable guide 35. The other extremity of the rod passes through a guide 36 which is supported in any desired or suitable manner and is spaced from the guide 35, the free extremity of the rod passing beyond the guide 36 and being screw threaded for the reception of a controlling nut 37. A suitable elastic member 38, such as a coil spring or the like, surrounds the rod 34 and is disposed between the guides 35 and 36. This spring 36 tends normally to hold the valve 33 seated 65 to close the opening 32 and by adjusting the

nut 37, the position of the valve 33 may be regulated with respect to its seat to open or close the opening 32 to permit or exclude the entrance of the outside air and by this means the vacuum or suction may be regulated.

A picker or brush 39, preferably in the form of a cross is provided for engaging and removing the cotton from the boll. The arms of the brush or picker are preferably arranged at right angles to each other, as shown more clearly in Fig. 3 and the edges of these arms are preferably serrated, as shown more clearly at 40 in Fig. 2. This brush or picker 39 preferably tapers from one end toward the other and passes through the collar 17, the latter being provided with slots or openings through which the arms of the picker pass and as the brush or picker is rotated, in a manner to be hereinafter set forth, the collar 17 will be also axially rotated. The brush or picker 39 is adapted to be shifted longitudinally through the collar 17 so as to strip the cotton from the picker. The collar 17 being fixed, it will be apparent that when the cotton adheres to the picker and the latter is shifted longitudinally through the collar, the cotton will be stripped from the brush.

The brush or picker is arranged so that the smaller end thereof will stand adjacent the edge of the picker nozzle and when in position will be located eccentrically with respect to the extremity of the picker nozzle.

Any suitable means may be provided for axially rotating the picker or brush 39, and a suitable and efficient means for accomplishing this purpose comprises a shaft 41, which terminates short of the picker 39 and is provided on its extremity adjacent the picker 39 with a tubular section 42, and a suitable bearing 43 may be provided on the picker nozzle for supporting the shaft. The tubular section 42 of the shaft 41 is adapted to receive an extension 44 of the picker 39, which latter is adapted to be telescoped into the tubular section 42 when the picker 39 is shifted longitudinally in one direction and the extension 44 of the picker may be secured for rotation with the shaft 41 in any desired or suitable manner, preferably by means of a key 45 which key will also permit longitudinal adjustment of the extension 44 into or out of the tubular section 42.

The picker 39 is preferably provided with a shoulder 46 beyond which a suitable yoke 47 loosely engages the picker so as to permit the picker to be axially rotated with respect thereto, and secured to the yoke is a suitable shifting member 48 preferably in the form of a wire or any other suitable material which may be pulled so as to move the picker 39 longitudinally.

Disposed between the collar 46 and the extremity of the tubular section 42 and sur-

rounding the extension 44 of the picker is a suitable elastic member 49, such as a coil spring or the like, which tends normally to hold the picker 39 away from the tubular section 42 and into an operative position so that the free extremity of the picker will stand adjacent the end of the picker nozzle and in a position to engage the cotton in the boll when the nozzle is held in an operative position. When the cotton has adhered to the picker 39, the latter may be shifted through the medium of the wire or member 48 and against the tension of the elastic member 49 to pull the picker through the collar 17, as shown in dotted lines in Fig. 2, to disengage the cotton from the picker, and when the tension on the member 48 is released, the elastic member 49 will return the picker 39 to its operative position, as shown in full lines in Fig. 2.

Motion may be imparted to the shafts 41 in any desired or suitable manner, preferably by means of gears 50 meshing with gears 51 which latter are secured for rotation with a shaft 52 which latter may be rotated through the medium of intermeshing gears 54, 55, the gear 54 being rotated in any desired or suitable manner, such as by means of a belt 56, which is driven from the shaft of the suction or exhaust fan within the casing 11. The shafts 41, if desired, may be provided with universal joints 57 and the shafts themselves may be constructed of any material suitable for the purpose and which will permit the tubular members 13 to be readily flexed without interfering with the operation of the shafts 41.

Any suitable means may be provided for automatically shifting the pickers 39 longitudinally. Suitable and efficient means for accomplishing this purpose comprises a bell crank lever 58 which is pivotally mounted upon any suitable support. The free extremity of the shifting member 48 is connected to one arm of the bell crank lever, and the other arm may be connected to an operating rod, or member 59. If desired, and as shown in the present exemplification of the invention, the free ends of one or more of the bell cranks may be connected to the same member 59, or one of the bell cranks may be connected to the member 59 and a link 60 may be provided for connecting the remaining bell cranks in series.

Slidably mounted in suitable bearings 61 secured to the vehicle 10 is a member 62 to which the extremity of the member 59 is connected and this member 62 is provided with a projection 63 preferably in the form of an ear or finger. Rotatably mounted upon the vehicle in suitable bearings is a crank 64 preferably in the form of a gear having a lateral projection 65 which is adapted to engage the projection 63 on the member 62 when the gear 64 is rotated so as to shift the

member 62 in one direction in its bearings 61. When the projection 65 passes out of engagement with the projection 63, during a continued rotation of the gear 64, the member 62 will be released and the tension exerted upon the elastic members 49 when the member 62 is moved in one direction will cause the member 62 to move in the opposite direction to position the projection 63 to be engaged by the projection 65 on the next rotation of the gear 64, thereby forming a tappet mechanism for automatically shifting the brush or picker 39 longitudinally.

The gear 64 preferably meshes with and receives its rotary motion from the gear 23 and obviously the gears 23, 64, may be of any desired size with respect to each other and may be so changed as to regulate or impart the desired number of longitudinal shifting movements of the picker 39.

Leading from the suction or vacuum creating casing 11 is a discharge pipe or passage 66 which delivers the cotton drawn into the casing through the tubular members 13 and chamber or tubular member 12 into a separator 67 from which separator the cotton will be discharged through the outlet 68 into the vehicle while the air will be discharged through the outlet 69 into the atmosphere.

While in the present exemplification of the invention the vehicle is illustrated with a tongue 79 by means of which it may be propelled through the cotton fields, it is to be understood that the vehicle may be motor propelled, in which event the usual gearing will be provided for connecting the motor with one of the axles of the vehicle.

With this improved construction and with the improved form of picking nozzle it will be apparent that the blasts of air will be directed across the opening of the picker nozzle into the boll when the latter projects into the nozzle and the whirling action of the blasts of air from the nozzles 20 will gradually separate or disintegrate the cotton in the boll. During this disintegration or separation of the cotton while in the boll, it will be engaged by the brush or picker 39 and the rapid axial rotation of the latter will gradually draw or pull the cotton from the boll. As the cotton accumulates on the picker or brush some of it will be drawn from the brush by the suction created in the tubular member 13 and through the nozzle 14 into the separator 67 and the cotton which still adheres to the picker and which is not removed by the suction will be stripped from the picker when the latter is longitudinally shifted. As the cotton falls from the picker it will be conveyed by suction through the nozzle 14 and into the separator 67 in a similar manner. It will also be apparent that by the provision of the valve 31 which is controlled by the operator, the picking nozzle

may be properly positioned with respect to the boll before the blasts of air are directed against the cotton to separate the latter.

A suitable seat 80 may be supported from the vehicle 10 in any desired or suitable manner and any number of these seats may be provided according to the number of picker nozzles employed, preferably one seat for each two nozzles. These seats are located 10 in close proximity to the ground and are provided for the operators who handle the nozzles and by means of which the nozzles may be readily directed into engagement with the plants. It will also be apparent 15 that the picking of the cotton is absolutely under the control of the operator by means of the valve 31, for by its use the air may be controlled so that only a sufficient amount will be directed to the nozzle to separate the 20 cotton on the plant into a light, fluffy form and the degree of suction in the tubes 13 may be regulated by the valve 33 to create a vacuum only sufficiently strong to take or draw away the cotton and leave the heavy 25 substance such as leaves, trash or the like, which would lower the grade of the cotton if mixed therewith.

In order that the invention might be fully understood, the details of the foregoing embodiment thereof have been thus specifically described but what I claim as new is—

1. A cotton picker including a picking nozzle, means for directing a blast of air across the nozzle to separate the cotton in 35 the boll, additional means for removing the cotton from the boll and means for shifting the last said means for removing the cotton therefrom.

2. A cotton picker including a picking 40 nozzle, means for directing a blast of air across the nozzle to separate the cotton in the boll, mechanical means for pulling the cotton from the plant and means for shifting the said mechanical means for removing the cotton therefrom.

3. A cotton picker including a picking 45 nozzle, means for separating the cotton in the boll, means adapted to engage and pull the cotton from the plant, means for removing the cotton from the last said means and means for shifting one of the last two said means with respect to the other.

4. A cotton picker including a picking 55 nozzle, means for separating the cotton in the boll, means adapted to engage and pull the cotton from the plant, means for removing the cotton from the last said means and means for shifting one of the last two said means with respect to the other, and means 60 for conveying the picked cotton away from the nozzle.

5. A cotton picker including a picking 65 nozzle, means for directing a blast of air from the periphery of the nozzle inward at an oblique angle to the periphery and in a

plane perpendicular to the longitudinal axis of the nozzle for separating the cotton in the boll, mechanical means within the nozzle for engaging and pulling the cotton from the plant, and means for operating said 70 mechanical means.

6. A cotton picker including a picking nozzle, means for directing a blast of air from the periphery of the nozzle inward at an oblique angle to the periphery and in a 75 plane perpendicular to the longitudinal axis of the nozzle for separating the cotton in the boll, mechanical means within the nozzle for engaging and pulling the cotton from the plant, and means other than the air blast 80 for operating said mechanical means.

7. A cotton picker including a picking nozzle, means adjacent the end of the nozzle for separating the cotton in the boll, mechanically operated means within the nozzle 85 and located eccentrically with relation thereto for engaging and pulling the cotton from the plant, means for stripping the cotton from the last said means and means for conveying the picked cotton away from the 90 nozzle.

8. A cotton picker including a picking nozzle, means whereby suction may be created within the nozzle, a supplementary picker within the nozzle, means for rotatably supporting said supplementary picker, and means for shifting said supplementary picker to remove the cotton therefrom.

9. A cotton picker including a picking 100 nozzle, means whereby suction may be created within the nozzle, a supplementary picker within the nozzle, means for rotatably supporting said supplementary picker, and means for longitudinally shifting said supplementary picker to remove the cotton 105 therefrom.

10. A cotton picker, including a picking 110 nozzle, means whereby suction may be created within the nozzle, a supplementary picker within the nozzle, means for rotatably supporting said supplementary picker, and means for longitudinally shifting the supplementary picker through its bearing to strip the cotton therefrom.

11. A cotton picker including a picking 115 nozzle, means whereby suction may be created within the nozzle, a supplementary picker within the nozzle, means for rotatably supporting said supplementary picker, and means for automatically shifting said 120 supplementary picker to remove the cotton therefrom.

12. A cotton picker including a picking 125 nozzle, means for conveying the cotton through the nozzle, a supplementary picker operating within the nozzle, a rotatable support through which the said supplementary picker is longitudinally movable, means for automatically shifting the supplementary picker through the support to strip the cot- 130

ton therefrom, and means for rotating said supplementary picker.

13. A cotton picker including a picking nozzle, means for conveying the cotton through the nozzle, a supplementary picker operating within the nozzle and eccentric thereto, a rotatable support through which the said supplementary picker is longitudinally movable, means for automatically shifting the supplementary picker through the support to strip the cotton therefrom, and means for rotating said supplementary picker.

14. A cotton picker including a picking nozzle, means for creating a suction in the nozzle, a rotatable and shiftable supplementary picker within the nozzle and adapted to engage and detach the cotton from the boll, means tending normally to hold the supplementary picker in a position with respect to the nozzle to engage and detach the cotton from the boll, and means for shifting the supplementary picker against the tension of the said holding means to strip the cotton therefrom.

15. A cotton picker including a picking nozzle, means for creating a suction in the nozzle, a rotatable and shiftable supplementary picker within the nozzle and adapted to engage and detach the cotton from the boll, means tending normally to hold the supplementary picker in a position with respect to the nozzle to engage and detach the cotton from the boll, and means for automatically shifting the supplementary picker against the tension of the said holding means to strip the cotton therefrom.

16. A cotton picker including a picking nozzle, means for creating a suction in the nozzle, a rotatable and longitudinally shiftable supplementary picker within the nozzle and adapted to engage and detach the cotton from the boll, means tending normally to hold the supplementary picker in a position with respect to the nozzle to engage and detach the cotton from the boll, and means for longitudinally shifting the supplementary picker against the tension of the said holding means to strip the cotton therefrom.

17. A cotton picker including a picking nozzle, means for creating a suction in the nozzle, a rotatable and longitudinally shiftable supplementary picker within the nozzle, means tending normally to hold the supplementary picker in a position with respect to the nozzle to engage and detach the cotton from the boll, and means for automatically shifting the supplementary picker against the tension of the said holding means to strip the cotton therefrom.

18. A cotton picker including a picking nozzle, means for creating a suction in the nozzle, a rotatable and longitudinally shiftable supplementary picker within the nozzle,

means tending normally to hold the supplementary picker in a position with respect to the nozzle to engage and detach the cotton from the boll, and means for automatically shifting the supplementary picker against the tension of the said holding means to strip the cotton therefrom, the last said means including tappet mechanism.

19. A cotton picker including a picking nozzle, means for creating a suction therein, means other than the suction means for directing a blast of air across the nozzle to separate the cotton in the boll, positive means for engaging the cotton and detaching it from the boll, means other than the first two said means for operating the said positive means, and means for bodily shifting the said positive means for removing the cotton therefrom.

20. A cotton picker including a picking nozzle, means for creating a suction therein, means other than the suction means for directing a blast of air across the nozzle to separate the cotton in the boll, positive means for engaging the cotton and detaching it from the boll, means other than the first two said means for operating the said positive means, and means for automatically shifting the said positive means bodily to strip the cotton therefrom.

21. A cotton picker including a picking nozzle, an axially rotatable picker adjacent the end of the nozzle for engaging and pulling the cotton from the boll, means for rotating said picker and means for shifting the rotatable picker with respect to the nozzle for disengaging the cotton from the said pulling means.

22. A device of the character described including an axially rotatable picker adapted to engage and pull the cotton from the plant, means for removing the cotton from the picker, means for shifting said axially rotatable picker and the cotton removing means one with respect to the other, means for rotating the picker, and a nozzle inclosing the picker.

23. A cotton picker including a picking nozzle, an axially rotatable picker adjacent the end of the nozzle for engaging and pulling the cotton from the boll, means for rotating the picker, means for shifting the rotatable picker with respect to the nozzle for disengaging the cotton therefrom, and means for conveying away the cotton thus disengaged.

24. A picker including a suction picking nozzle, an axially rotatable mechanical picker adjacent the end of the nozzle for engaging and pulling the cotton from the plant, means for rotating the picker, and means for shifting the rotatable picker with respect to the nozzle for disengaging the cotton from the said rotatable picker.

25. A cotton picker including a suction

picking nozzle, an axially rotatable mechanical picker adjacent the end of the nozzle for engaging and pulling the cotton from the boll, means for rotating the picker and 5 means for automatically shifting the said mechanical picker with respect to the nozzle for disengaging the cotton therefrom.

In testimony whereof I have signed my

name to this specification, in the presence of two subscribing witnesses, on this 12 day 10 of September A. D. 1908.

WILLIAM W. FARNSWORTH.
